(57) **CLAIM**

The ornamental design of kneeling stabilization and support roll, as shown and described.

DESCRIPTION

FIG. 1 is an isometric view from the front/left side of the kneeling stabilization and support roll.

FIG. 2 is a left-side view thereof.

FIG. 3 is a right-side view thereof.

FIG. 4 is a top view thereof.

FIG. 5 is a bottom view thereof.

FIG. 6 is a front view thereof.

FIG. 7 is a back view thereof.

FIG. 8 is an isometric view from the front/left side thereof depicted in use; and,

FIG. 9 is an isometric and exploded and open view from the front/left side thereof.

The broken lines represent environmental features of the support roll that form no part of the claim. The dash-dot lead lines of the exploded view form no part of the claim.

1 Claim, 6 Drawing Sheets
